UNITED STATES PATENT OFFICE.

AMOS H. MESSEY, OF CONCORD, NEW HAMPSHIRE.

STEAM-ENGINE.

SPECIFICATION forming part of Letters Patent No. 364,363, dated June 7, 1887.

Application filed January 13, 1887. Serial No. 224,176. (No model.)

To all whom it may concern:

Be it known that I, AMOS H. MESSEY, a citizen of the United States, residing at Concord, in the county of Merrimac and State of New Hampshire, have invented certain new and useful Improvements in Steam-Engines, of which the following is a specification.

The object of this invention is to simplify the construction of a steam-engine, lessen the operative parts, and consequently dispense with much needless friction, thus acquiring more power with a given amount of fuel. These results are attained by the mechanism described in the following specification and illustrated 15 in the accompanying drawings, forming part hereof, of which—

Figure 1 is an end elevation, partly in section, representing my invention when taking the form of a stationary engine. Fig. 2 is a 20 side elevation of the same. Fig. 3 is an enlarged detail view, showing a form adapted for a double-action engine. Fig. 4 represents a detail of my improved revolving piston, showing a portion in section, and Fig. 5 is an 25 edge view of the same.

Similar reference-letters indicate corresponding parts.

The piston-rod A takes the place of a driving-shaft in an ordinary engine, and the piston 30 B comprises a thin disk, b, which, for convenience of manufacture, is formed separate from its hub b', to which it is attached by bolts passing through a collar, b'', the said disk, and a flange on said hub. On the periphery of said 35 disk are formed two or more arms, b'', which may project at an angle or radially therewith, as seen in Fig. 4. To these are bolted the follower-plates b''. The said piston-rod A is supported in bearings provided upon a suitable 40 engine-bed, C, upon which is formed or attached a circular plate, C', having a central opening, e, to accommodate said piston-rod and the cap of the bearing nearest to it, as in Fig. 45. To this plate is bolted the cylinder or housing for the revolving piston B. This consists of the parts D D', which are bolted together through their respective flanges d d', and secured to the engine-bed by bolts c', joining the part D to the plate-piece C'. Each of these 50 parts is provided with a semicircular groove, (shown, respectively, at d' d''), which form the

annular chamber E, which may have the supply-ports d' and exhaust-port d'' at the required point.

The bearings in the engine-bed carrying the 55 piston-rod are formed perfectly concentric with the chamber E. A packing of some kind is necessary for both the disk b and follower-plates b''. Many forms could be devised. Two simple forms I show in Figs. 4 and 5. The first I will describe consists of a piece of steel, F, which resembles "angle-iron" in form, and is so bent and shaped as to pack the follower as well as the periphery of the disk, and when its ends are welded or riveted together this 65 makes a packing for one side of two followers and the periphery of the disk all in one continuous piece, which is held in position by the follower-plates b'', which are bolted to either side of an arm, b'', and the strip G, resting upon the parts f f, secured by bolts g, passing between either of said parts f f and threaded to the disk b. The sides f' of the packing F bear against the sides of the chamber E and project far enough beyond the follower-plates 70 b'' to be expanded within said chamber by the action of the steam, and the sides f' f'' may be beveled slightly from the bottom outward and bear in a groove, d'', formed in either of the semicircular grooves d' d'', as seen in Fig. 80 3, and these will also be expanded and made tight by the action of the steam in the chamber E. The other form of packing which I have shown consists of two separate parts for the disk and the follower-plates, respectively, H 85 H', the parts H being cut the exact length from center to center of either of the arms b'' on the line of the periphery of the disk, and having their ends notched or slotted to receive one-half the thickness of the arms b'', they being 90 about double the width of the said disk b, and having their edges beveled slightly to fit the grooves d'', as are the sides f' f'' of the packing F, the parts H' being simply ordinary ring spring-packing closely fitting the chamber E, 95 and having their ends bear against the arms b'', and resting with some force upon two adjacent parts H. These are held in place by the follower-plates b'', which are turned a moderately loose fit for chamber E.

In Figs. 1 and 2 a fly-wheel, I, is shown mounted on one end of the revolving piston-

rod A, and a small pulley may be placed between the bearings for running a governor.

In a double-action engine either of the supply-ports d^4 may be used, and by closing one 5 and opening the other the engine is reversed without the necessity of either slide or rotary valves or eccentrics.

A three-way valve, J, may be used to advantage on either a double or single action engine. In case of a locomotive-engine, by turning the plug j , the exhaust may be decreased as desired, which is equivalent to shortening the throw of the ordinary slide-valves, and by giving said plug one quarter-turn in one direction the engine will exhaust by way of the ways j^1 j^2 and the outlet j^3 directly into the open air, thus taking the draft caused by the exhaust-steam in the smoke-stack away from the fire-box and checking the fire. The outlet 20 j^3 may be provided with a screen, j^4 , to prevent a possible entrance by suction, when the steam is shut off, of cinders or other dirt to the piston-housing.

Having described my invention, what I

claim, and desire to secure by Letters Patent 25 of the United States, is—

1. In a steam-engine, the combination of a rotary piston rod or shaft, a piston attached thereon consisting of a disk having radial arms and follower-plates bolted thereto, and 30 a suitable cylinder or housing formed in two parts provided with annular grooves adapted to receive said piston, and supply and exhaust ports, substantially for the purpose set forth.

2. In a rotary engine, the combination, with 35 the piston-housing and piston rod or shaft, of a piston comprising a disk firmly secured to said piston-rod, as shown, having two or more radial arms, follower-plates bolted thereto, and the steam-packing, all constructed substantially in the manner and for the purpose set forth.

In testimony whereof I affix my signature in presence of two witnesses.

AMOS H. MESSER.
